UNITED STATES PATENT OFFICE.

EDMUND P. KINNE, OF ALLIANCE, OHIO, ASSIGNOR TO AMERICAN STEEL FOUNDRIES, OF NEW YORK, N. Y., A CORPORATION OF NEW JERSEY.

CAR-COUPING.

1,151,691.

Specification of Letters Patent. Patented Aug. 31, 1915.

Application filed November 22, 1913. Serial No. 802,380.

To all whom it may concern:

Be it known that I, EDMUND P. KINNE, a citizen of the United States, and resident of Alliance, in the county of Stark and State 5 of Ohio, have invented certain new and useful Improvements in Car-Couplings, of which the following is a specification.

My invention relates to car couplers and has particular reference to a novel coupler 10 similar to the coupler disclosed in the co-pending application of Janney & Kinne, Serial No. 603,858, filed Jan. 21, 1911.

Due to the requirements of the railroads and the constant efforts of the Interstate 15 Commerce Commission for improvements in railway appliances which would tend to reduce the dangers to passengers and employees, many changes in coupler equipment have taken place. Much of the loss 20 in property damage and personal injury is caused by defective couplers. It is not uncommon for a train to become parted due to unlocking of the coupler caused by insufficient anti-creep provisions. Further, many 25 trainmen are injured by passing between cars in the act of coupling because of failure of the lock to unseat from the lock-set, necessitating manual adjustment.

One of the principal objects of my invention 30 is to provide an efficient lock-set together with effective means for unseating the lock from the lock-set. In the present construction this is accomplished by forming the lock-set on the side corresponding 35 to the locking face of the coupler, or, in other words, at a point which is close to if not intersected by the arc of movement of the knuckle tail. On the return movement of the knuckle it will be seen that the lock 40 is positively pulled from the lock-set if it has not theretofore been unseated in the opening movement.

A further object is to provide an efficient 45 anti-creep, which shall be positive, which shall have no loose parts or triggers and which cannot fail to operate.

A third object is to provide efficient knuckle throwing means whereby the knuckle 50 may surely be thrown from the side of the car without necessity for the workmen passing between the cars.

My invention will be more readily under-

stood by reference to the accompanying drawings, wherein,

Figure 1 is a transverse vertical section 55 of a coupler constructed in accordance with my invention, the lock being shown in normal locked position; Fig. 2 is a similar view showing the lock in lock-set position; Fig. 3 is a similar view showing the knuckle fully 60 opened with the lock unseated from the lock-set and resting on the tail of the knuckle; Fig. 4 is a similar view showing the lock and knuckle opener in the position they will assume after the knuckle has been 65 thrown; Fig. 5 is a horizontal section showing the guides for the lock; Fig. 6 is a perspective view of the lock; Fig. 7 is a longitudinal vertical section on the line 7—7 of Fig. 5, showing the lock in normal locked 70 position, and, Fig. 8 is a similar view showing the lock in anti-creep position; that is, the position the lock would assume after the creeping action had begun.

Referring more particularly to the drawings, it will be seen that I provide a coupler head 10, in which is pivoted a knuckle 11, having a tail 12, and a locking face 13. On the upper rear portion of the knuckle tail is an upstanding rib 14, adapted to assist in unseating the lock, as will be herein-after described. Within the head 10, I provide a groove 15, acting as a guide for one side of the lock 16, and co-operating with an extension or rib 17 thereon. In order to assure the proper vertical travel of the lock and at the same time permit of necessary oscillation when in raised position, I provide a guide rib 15', extending inwardly from the rear coupler wall. Midway in the height 85 of the wall on the guard arm side of the coupler, I provide an offset portion forming a ledge 18, which acts as a lock-set. A support 19 is provided for the lock at the bottom. The lock 16 is provided with a toe 20, 90 which co-operates with the ledge 18, and also with the support 19 when the lock is in normal position. It will be noted that the lock 16 is provided with a staple 21, to which a lifter 22, is attached and that the lifter acts 100 on the lock to lift the same from a point to the right of the center of gravity of the lock. Thus the lock tends to swing to the right at its bottom, assuring the co-operation

of the toe 20 with the ledge 18. As a positive means for causing the coöperation of toe 20 with ledge 18, it will be seen that the lock coöperates with the knuckle thrower 23, just as it reaches a point where the toe 20 is above the ledge 18, and as the contact of the thrower 23 with the lock 16 is at a point to the left of its support, the lock will be forced to swing and bring it into lock-set 5 position.

The knuckle thrower is similar to that disclosed in earlier applications filed by me and need not be specifically described except to say that the thrower is provided with 15 trunnions 24, coöperating with seats 25, in the head and with a downwardly extending foot 26, coöperating with the knuckle tail and through swinging motion caused by the extreme lifting of the lock 16, forces the 20 knuckle outwardly in a line not unopposed to the line of travel of the knuckle tail.

The anti-creeping provision, as best shown in Figs. 7 and 8, consists of a ledge 28, formed from the wall of the coupler and extending transversely of the coupler shank, 25 tending transversely of the coupler shank, this ledge lying at a point slightly above the upper, rear edge 16' of the lock when the lock is in normal position. Any creeping action of the lock will tend to rock the same 30 thus causing the point 16' to project beneath the plane of the ledge 28, as shown in Fig. 8. Thus any creeping of the lock is effectually overcome. Also provided on the upper face 35 of the knuckle tail 12 and extending transversely of the rib 14 is a hump or upward projection 27, as best shown in Figs. 1, 2 and 5. As shown, this projection is triangular in cross section and is adapted to contact the toe 31, of the lock as the knuckle is 40 opened, the lock being raised out of contact with the lock seat. As the knuckle continues to open the projection 31 passes the high point on the projection 27, then rides down the incline on the other side of the triangle, 45 thus moving the lock to the left and bringing the toe 20 out of a plane where it may engage with the ledge 18. As the lock rides down the incline it will descend bodily, the toe 20 then being below the ledge 18, and 50 any further movement of the knuckle will not tend to cause engagement in such manner as to again seat the lock on the lock-set. The lock rides in such manner on the knuckle tail during both the opening and 55 closing movement being retained in proper relation by reason of the rib 14. However, on the closing movement of the knuckle tail, assuming that the lock may have become reseated on the lockset, the projection 31 on 60 the lock will be contacted by the projection 27 on the knuckle tail, thus positively pulling the lock from the lockset and permitting it to drop into locked position.

It will be understood that the knuckle thrower 26 is rotated by contact of the arm

23 with the top of the lock 16. In order to assist in the throwing action I provide a fulcrum for the lock 16, whereby the lock swings around a point of contact between a portion of the lock and a projection on 70 the guard arm side of the coupler wall. As shown, the lock is provided with an upward extension 29 of the rib 17, this extension being adapted to coöperate with a stop 30 at the top of the vertical groove 15, the stop 75 acting as a fulcrum around which the lock may pivot when lifted to its extreme upward limit. This provides for a free actuation of the knuckle thrower due to the removal of any binding or friction which might be occasioned in a straight lifting movement without providing a point on which the lock could fulcrum. One of the principal advantages in such construction is in that the knuckle may be thrown with a shorter movement of the lifting element. By the elimination of frictional or binding resistance such shorter lift is possible without unnecessarily increasing the force necessary to throw the knuckle. 90

By the construction herein shown I am enabled to provide a full locking face for the lock on the guard arm side of the coupler and also to provide a lockset on the guard arm side whereby locksetting is assured and unseating from the lockset is positively assured. 95

It is obvious that certain modifications may be made in the construction shown and such modifications as are within the scope 100 of my claims I consider within the spirit of my invention.

I claim:

1. In a car coupler, the combination of a head and a knuckle pivoted therein, a vertically movable locking member, locksetting means projecting outwardly from a wall on the guard arm side of the head, said locking member being caused to coöperate with said locksetting means by swinging movement of the lock in a line substantially parallel with the movement of the knuckle tail, and anti-creeping means, on the coupler rear wall said means being active only on a backward locking movement of the lock, substantially 110 as described.

2. In a car coupler, the combination of a head having an interior stop near the top thereof on the guard arm side, a knuckle pivoted in said head, a bell crank knuckle thrower, a locking member vertically movable within said head, said locking member having a portion adapted to contact the stop in said head and fulcrum therearound, another portion of the lock contacting said bell-crank knuckle-thrower whereby to rotate the same on its pivot, substantially as described. 120

3. In a car coupler, the combination of a head having a stop therein within the upper 130

portion thereof, a knuckle pivoted in said head, a bell crank knuckle thrower mounted on trunnions within said head and mounted for swinging movement in a line substantially parallel with the line of movement of the knuckle tail, a vertically movable locking member having a portion adapted to contact the stop in said head and fulcrum

theraround, another portion of said lock contacting said bell crank knuckle thrower 10 whereby to swing the same and rotate said knuckle, substantially as described.

EDMUND P. KINNE.
